UNITED STATES PATENT OFFICE.

LOUIS E. F. WACHTER, OF NEW YORK, N. Y.

WATCH CRYSTAL AND BEZEL.

1,288,309.

Specification of Letters Patent. Patented Dec. 17, 1918.

Original application filed October 17, 1917, Serial No. 197,006. Divided and this application filed April 6, 1918. Serial No. 226,982.

To all whom it may concern:

Be it known that I, LOUIS E. F. WACHTER, a citizen of the United States, residing in the city, county, and State of New York, have invented certain new and useful Improvements in Watch Crystals and Bezels, of which the following is a specification, reference being had to the accompanying drawing, illustrative of one particular embodiment of my invention, this application being a division of my application, Serial No. 197,006, filed October 17, 1917.

This invention relates to crystals as the term broadly applies, that is a transparent protecting cover for the face of a watch, clock or other article where the dial must be visible and at the same time protected. In particular, instead of the use of glass for crystals, celluloid and other transparent materials are used, and in the case of celluloid the physical characteristics of the material necessitate new methods of attachment.

Among the objects of this invention are to provide better means of overcoming the difficulties in attaching celluloid, or like material, and to secure them in a way which assures under all conditions a tight joint between the transparent disk and the attaching rim, under the various conditions to which the material is subjected. I accomplish this by making a pliable, resilient and transparent face cover, the form and construction of which are such that any shrinkage that might take place will not produce a loosening in the joint.

In the particular species of crystal and attaching rim or bezel, to which this divisional application is addressed, I have illustrated in the accompanying drawing one form, in which—

The crystal O, as shown in fragmentary view, has a bend near the edge which is reentrant and again turns outward as at o, thereby forming a recess below the surface of the inner side of the crystal O, which engages a projection or rib O'' on the bezel O'. As shown, the surface of the crystal, where it engages the bezel, has the circumferential projection O'' so that it forms an outer portion of slightly greater diameter than the annular reentrant surface portion below it, which merges into the brim o, and which engages the underside of the bezel.

These results are attained by the features as shown clearly in the drawings, namely,

the brim o is of considerably greater diameter than the minimum diameter of the bezel opening, and likewise the crystal at O'' is normally of greater diameter than the minimum diameter of the bezel, so that when the crystal is inserted in the bezel the crown portion of the crystal contacts sufficiently to permit the insertion of the crystal crown through the bezel opening, until the brim engages the underside of the bezel. When in position the normal shape of the crystal causes suitable pressure of engagement with the bezel after the release, for the necessary tight fit of the crystal between the bezel, crown and the brim portion.

It will be seen that the crystal may be inserted from the inside to engage the bezel, and when snapped in position will be held against inward displacement, while the edge of the crystal turning outward at o will prevent the outward displacement of the crystal in spite of any substantial contraction or shrinkage.

In watches where the bezel is very low and it requires a very heavy surface crown on the crystal, the reentrant and brim portion would be of much thinner material to fit such a low bezel.

It will be seen that the construction of bezel and crystal is such as may be readily made in the course of manufacture, with tools and methods used by those familiar with the art. Variations in thickness and dimensions of material become important in the new art of celluloid or like material for these articles, but variations in dimensions and form and sizes may be made without departing from my invention.

Relatively thin material may be used for the face or transparent closure, whereby the desired elasticity and spring for insertion and otherwise, are provided and proper transparency in such materials as celluloid is assured, while various other advantageous features necessary for commercial success are accommodated.

What I claim and desire to secure by Letters Patent is:

1. In combination in a watch or like article, a bezel, a crystal having its main surface merging into a beveled periphery, a projecting ridge extending from said beveled portion, and engaging the upper part of the rim of the bezel, and having in conjunction therewith a flange brim constituting the

edge of the crystal engaging the under side of said bezel.

2. In combination in a watch or like article, a bezel having an inwardly-projecting rim portion, a crystal having a lateral groove formed in a depending side wall engaging said projecting rim portion, and a curved portion merging into a peripheral edge on said crystal engaging the under side 10 of said bezel.

3. In combination in a watch or like article, a bezel, a crystal having a concave re-entrant portion of larger diameter than the peripheral bezel opening constituting a 15 crown portion, and engaging the bezel opening, in conjunction therewith a curved portion merging into a peripheral flexible brim being a continuation of said crown portion and pressing against the underside of the 20 bezel, and coöperating with the re-entrant portion of the crown, thereby clasping the upper and underside of the bezel rim.

4. In combination in a watch or like article, a bezel, a flexible crystal having near its 25 periphery a bend forming a fold laterally

offset from the concave side of the crystal and merging into a brim bent radially outward and of substantially greater diameter than the minimum diameter of the outer wall of the fold, and substantially greater 30 than the minimum diameter of the bezel opening.

5. In combination in a watch or like article, a closure for the face comprising a bezel having an inner opening, a flexible crystal 35 having near its periphery a circumferential projection within the plane of the outer face of the crystal, and having a brim of greater diameter merging with said circumferential projection, whereby said projection and said 40 brim engage the inside and the outer portion of the bezel on opposite sides of the portion of the bezel of lesser diameter than the projection and the brim of the crystal.

Signed at New York, this 5th day of 45 April, 1918.

LOUIS E. F. WACHTER.
